UNITED STATES PATENT OFFICE.

LOUIS L. MARTIN, OF TORONTO, ONTARIO, CANADA.

DESIGN FOR A CASE OF A COIN-CONTROLLED VENDING APPARATUS.

No. 38,793.

Specification for Design

Patented Sept. 10, 1907.

Application filed June 29, 1907. Serial No. 381,577. Term of patent 14 years.

To all whom it may concern:

Be it known that I, LOUIS L. MARTIN, a citizen of the Dominion of Canada, residing at the city of Toronto, in the county of York and Province of Ontario, Canada, have invented a new, original, and ornamental Design for the Case of a Coin-Controlled Vending Apparatus, of which the following is a specification, reference being had to the accompanying drawing, forming part thereof.

The drawing is a perspective view of the case.

I claim:

The ornamental design for the case of a coin-controlled vending apparatus, as shown.

LOUIS L. MARTIN.

Witnesses:

J. EDW. MAYBEE,
F. W. MCKENDRICK.
